(57) **CLAIM**

The ornamental design for a hose connection thimble, as shown and described.

DESCRIPTION

FIG. 1 is a top front perspective view of a hose connection thimble showing my new design;

FIG. 2 is a left-side elevational view thereof;

FIG. 3 is a right-side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken lines shown in the figures are included for the purpose of illustrating elements of the hose connection thimble and form no part of the claimed design.
